UNITED STATES PATENT OFFICE.

ARTHUR E. BAUMAN, OF AKRON, OHIO.

DESIGN FOR A VEHICLE TIRE TREAD OR SIMILAR ARTICLE.

Application filed June 28, 1922. Serial No. 2,875. Term of patent 14 years.

To all whom it may concern:

Be it known that I, ARTHUR E. BAUMAN, a citizen of the United States, residing at Akron, in the county of Summit and State of Ohio, have invented a new, original, and ornamental Design for a Vehicle Tire Tread or Similar Article, of which the following is a specification, reference being had to the accompanying drawing, forming part thereof, and in which—

I claim:—

The ornamental design for a vehicle tire tread or similar article, as shown.

ARTHUR E. BAUMAN.
